UNITED STATES PATENT OFFICE.

JOHN GREENWOOD, OF ROCHESTER, NEW YORK.

IMPROVEMENT IN JOURNAL-BOXES FOR SHAFT-HANGERS.

Specification forming part of Letters Patent No. **159,260**, dated February 2, 1875; application filed October 24, 1874.

To all whom it may concern:

Be it known that I, JOHN GREENWOOD, of the city of Rochester, in the county of Monroe and State of New York, have invented a certain new and useful Improvement in Hangers for Shafting; and I do hereby declare that the following is a full, clear, and exact description of the construction and operation of the same, reference being had to the accompanying drawings, in which—

Figure 1 is an end elevation, showing my improvement applied to a hanger. Fig. 2 is a longitudinal vertical section of the journal-box. Fig. 3 is a perspective view of the same.

My invention relates to hangers for shafting; and consists of a box made in one piece, and constructed with lips or flanges for catching the drippings at the ends of the box, and with a closed chamber beneath for holding the drippings, as hereinafter described.

In the drawings, A represents the box, which is supported in a forked hanger suspended from the ceiling, the connection being made by means of a bolt or pin, which passes transversely through the box beneath the bearing, as shown. The box rocks on this bolt, and is adjusted by means of a check-screw, as usual. The box A is cast in a single piece, and consists of the bearing b, through which the shaft passes; an oil-cup, c, above it, for applying the oil; and an oil chamber or receptacle, d, below the box, for catching the drippings. In the act of casting this chamber is cored out, so as to leave the receptacle d closed at the bottom and the sides, the only openings being formed at the ends, as shown, at ff, and at the bottom, which is filled by a plug or stopper, g, for the purpose of drawing off the oil when a quantity has collected. At the ends of the box are lips or flanges h h, projecting out some distance beyond the ends of the bearing b, and standing upward, so as to catch the drippings from the ends of the box without escaping or running down over the sides.

The oil escapes from the ends of the box and strikes upon the lips h h, and passes through the openings ff into the chamber d, and settles to the bottom; and when the chamber is filled, the oil is drawn off by removing the plug g from the nipple k.

Boxes with oil-receptacles have before been employed, but are generally open, so that dust can settle in the oil and gum it, thereby rendering it unfit for second use.

The distinctive feature of my invention is the lips or flanges h h at the ends of the box, projecting beyond the bearing portion and standing upward, so as to catch the drippings, thereby preventing the oil from running down the sides of the box and besmeared the same. Another feature is the chamber d beneath the bearing, made closed, except at the inlet-openings ff, so that but very little dust or dirt can enter.

A hanger thus constructed can be cast in a single piece, and is, therefore, very cheap and simple.

Having thus described my invention, I do not claim, broadly, a box having a dripping-chamber for catching the oil; but

What I claim is—

The box A, cast in a single piece, with the oil-cup c, bearing b, and oil-chamber d arranged below said bearing, and constructed with the lips h, projecting beyond the ends of the bearing, and with the opening f and the nipple k, for receiving the plug g, and otherwise constructed as herein shown and described, for the object specified.

In witness whereof I have hereunto signed my name in the presence of two subscribing witnesses.

JOHN GREENWOOD.
